CATHODE ASSEMBLY

Rudolph O'Larte, Rego Park, N. Y., and Kurt Speck, Palisades Park, N. J., assignors to Jacques Kreisler Manufacturing Corporation, North Bergen, N. J., a corporation of New Jersey

Application June 18, 1945, Serial No. 600,028

6 Claims. (Cl. 250—162)

1

This invention relates to a cathode assembly for a cathode-ray tube or the like.

One object of the present invention is to provide improved means for supporting the heating element of the cathode and to facilitate the assembly of said heating element with the cathode and the tubular member in which the cathode is mounted.

Another object of the invention is the provision of a cathode assembly in which the heater element is carried by releasably attached supporting means to facilitate replacement of the heating element in the cathode assembly.

The above and other objects, features and advantages of the invention will be fully understood from the following description considered in connection with the accompanying illustrative drawings.

In the drawings:

Fig. 1 is an end view of a cathode assembly embodying the present invention;

Fig. 2 is a sectional view on the line 2—2 of Fig. 1;

Fig. 3 is a view similar to Fig. 2 showing another form of the invention;

Fig. 4 is an end view of retaining means forming part of the cathode assembly of the present invention;

Fig. 5 is a sectional view on the line 5—5 of Fig. 4.

Referring now to the drawings in detail, the cathode assembly 10, which is intended for use in a cathode-ray tube as part of the electron gun, comprises a tubular member 12 formed of sheet metal. Said tubular member is preferably of the construction illustrated in our application, Serial No. 588,230, filed April 13, 1945, and comprises two semi-cylindrical parts 14 and 16 having lateral extensions 18 which define small tubular parts for mounting the cathode assembly on insulation rods (not shown) provided in the electron gun mounted in the cathode-ray tube. A sheet metal disk 20 provided with an electron aperture 22 is positioned and secured at one end of tubular member 12, as disclosed herein and in said application, and a tubular cathode 24 carried by an annular disk 26 is mounted axially of tubular member 12 and is held in spaced relation to disk 20 by an annular spacing member 28 and by spring retaining means 30.

The cathode heating element 32, which is positioned within the tubular cathode 24, is carried and supported by an insulation member 34, hereinafter more specifically described, which is releasably held in position by parts of the retain-

2

ing means 30. The retaining means 30 is formed of resilient sheet metal and comprises a forward annular portion 36 having a peripheral flange 38 and a plurality of resilient arms 40 which extend longitudinally of tubular member 12 in engagement with the inner surface thereof. Each of said arms 40 is provided with an outwardly pressed transverse rib 42 positioned so that it engages tubular member 12 in an annular groove 44 pressed therein. Annular portion 36 of the retaining means is provided with a plurality of integral struck out spring elements or fingers 46 which resiliently engage the cathode carrying disk 26 and press the latter against the spacing member 28, said spacing member being thereby pressed against the apertured disk 20. The retaining means 30 as thus far described is the same as in the cathode assembly of our above mentioned application. In accordance with the present invention, however, the arm 40 of retaining means 30 is provided with integral parts which releasably engage the heater support 34 for holding the latter in position on tubular member 12. More specifically, as here shown, arms 40 of retaining means 30 are provided with outwardly pressed transverse ribs 48 and insulation supporting member 34, which as here shown is in the form of a disk, is provided with circumferentially spaced notches 50 in which said ribs 48 are movably positioned, respectively, and resiliently engage said insulation supporting member 34 for holding the latter on tubular member 12.

The insulation supporting member 34 is provided with terminal members 52. Each of said terminal members comprises a bent flat wire provided with a pair of spaced lateral projections 54. The insulation supporting member 34 is provided with a pair of openings 56 in which the terminal members 52 are positioned, the companion projections 54 of each terminal member engaging the inner and outer sides, respectively, of member 34 for holding the terminal member against movement transversely of the plane of member 34. Metal strips 58 are positioned between the opposite sides of each terminal member 52 and are welded or otherwise secured to said terminal members for preventing movement of the opposite sides of said terminal members, respectively, toward each other. It will be understood that the strips 58 are inserted in position after the terminal members are positioned in the companion openings 56 and that after the terminal members are positioned in their companion openings of member 34. Strips 58 hold the op-

posite sides of the terminal members against the adjacent sides of the companion openings 56. As shown in Fig. 2, the ends of the heater element 32 are secured to the inner ends of the companion terminals 52, preferably by positioning the end of the heater element between the inner end portions of the opposite sides of the companion terminal member and by welding the end of the heater element to said end portions of the companion terminal member. It will be understood that, as usual, the heater element is coated with insulation material, except at the ends which are secured to the terminal members 52.

The heater element 32 is assembled with the supporting member 34 and forms a unitary sub-assembly therewith. In producing the complete cathode assembly, the sub-assembly comprising the supporting member 34 with the attached heater element 32 is mounted on tubular member 12, heater element 32 being positioned within the tubular cathode 24 and supporting member 34 being resiliently engaged by the ribs 48 of the retaining means 30.

The construction illustrated in Fig. 3 is the same as described above except in respect to the terminals and in respect to the manner in which the heating element 32 is attached to the insulation supporting member. As here shown, the insulation supporting member or disk 34A instead of being provided with one opening for each terminal member is provided with a pair of openings 60 and 62 for each terminal member, openings 62 having an additional function which will presently appear. Each terminal member 52A is formed of a piece of wire, which is preferably of circular cross-section, bent into the form shown in Fig. 3 to provide the laterally spaced legs 64 and 66 which are received in the companion openings 60 and 62. The outer bent end portion of the wire is twisted for providing the outer terminal portions 68, and the inner end portions of legs 64 and 66 are twisted together as indicated at 70, one of said inner end portions being longer than the other and bent into a transversely extending portion 72 to which the ends of the heater element 32 are welded or otherwise suitably secured. It will be noted that end portions 74 of the heater element 32 may extend into companion openings 62, respectively. In manufacturing the sub-assembly illustrated in Fig. 3, the terminal members 52A are secured to the supporting member 34A and then the ends of the heater element are secured to the inner transverse terminal portion 72, respectively, at such points longitudinally of the end portions of the heater element that the forward end of the latter is spaced properly from the inner surface of the forward end of the tubular cathode 24, openings 62 providing means to receive the end portions of the heater element which extend rearwardly of the terminal portion 72. This construction provided a convenient means for adjusting the position of the heater element 32 longitudinally of cathode 24 and also facilitates the attachment of the terminal members to the supporting member 34A and to the end of the heater element.

It will be understood that various changes in the details of construction and in the arrangement of parts may be made without departing from the underlying idea or principles of the present invention within the scope of the appended claims, and it will be noted that the present application is a continuation-in-part of our above mentioned application, Serial Number 588,230.

Having thus described our invention, what we

claim and desire to secure by Letters Patent is:

1. A sub-assembly for a cathode which comprises a tube provided with an electron aperture at one end thereof, a tubular cathode positioned within said tube axially thereof, and a heater in said cathode; said sub-assembly comprising said heater and a support therefor, said support comprising an insulation disk provided with two sets of spaced openings, each set comprising two openings and the openings of the two sets being symmetrically disposed at opposite sides, respectively, of the axis of said disk, a pair of terminal members secured to said disk, one of said terminal members having portions extending through the two openings, respectively, of one of said sets and electrically connected to one end of said heater and the other of said terminal members having portions extending through the two openings, respectively, of the other set and electrically connected to the other end of said heater.
2. A sub-assembly for a cathode which comprises a tube provided with an electron aperture at one end thereof, a tubular cathode positioned within said tube axially thereof, and a heater in said cathode; said sub-assembly comprising said heater and a support therefor, said support comprising an insulation disk provided with two sets of spaced openings, each set comprising two openings and the openings of the two sets being symmetrically disposed at opposite sides, respectively, of the axis of said disk, a pair of terminal members secured to said disk, one of said terminal members having portions extending through the two openings, respectively, of one of said sets and electrically connected to one end portion of said heater and the other of said terminal members having portions extending through the two openings, respectively, of the other set and electrically connected to the other end of said heater, one of the openings of each set providing a space to receive an end portion of the heater.

3. A sub-assembly for a cathode which comprises a tube provided with an electron aperture at one end thereof, a tubular cathode positioned within said tube axially thereof, and a heater in said cathode; said sub-assembly comprising said heater and a support therefor, said support comprising an insulation disk provided with a pair of openings symmetrically disposed in spaced relation at opposite sides of the axis of the disk, a pair of terminal members secured in said openings, respectively, and electrically connected to the ends of said heater, each of said terminal members comprising a bent wire having two sides extending through one of said openings, one of said sides having spaced lateral projections engaging the disk at the opposite sides, respectively, thereof for preventing movement of the terminal member axially of the disk.

4. In a cathode assembly which comprises a tube provided with an electron aperture at one end thereof, a tubular cathode positioned within said tube axially thereof, and a heater in said cathode; the combination with said first mentioned tube and said heater of an insulation member which supports said heater and is positioned at and closes the other end of said first mentioned tube, terminals carried by said member and electrically connected to said heater, said insulation member comprising a disk having peripherally spaced notches in its edge, and a plurality of spring arms carried by said tube and releasably engageable with said disk in said notches, respectively, for holding the disk in position.
5. In a cathode assembly which comprises a

tube provided with an electron aperture at one end thereof, a tubular cathode positioned within said tube axially thereof, and a heater in said cathode; the combination with said first mentioned tube and said heater of an insulation member which supports said heater and is positioned at and closes the other end of said first mentioned tube, terminals carried by said member and electrically connected to said heater, said disk being provided with two sets of spaced openings, the openings of the two sets being symmetrically disposed at opposite sides of the axis of said disk, a pair of terminal members secured to said disk, each of said terminal members having portions extending through the openings of one of said sets and electrically connected to an end portion of said heater.

6. In a cathode assembly which comprises a tube provided with an electron aperture at one end thereof, a tubular cathode positioned within said tube axially thereof, and a heater in said cathode; the combination with said first mentioned tube and said heater of an insulation member which supports said heater and is positioned at and closes the other end of said first mentioned tube, terminals carried by said member and electrically connected to said heater, said disk being provided with a pair of openings symmetrically

disposed in spaced relation at opposite sides of the axis of the disk, a pair of terminal members secured in said openings, respectively, and electrically connected to the ends of said heater, each of said terminal members comprising a bent wire having two sides extending through one of said openings, one of said sides having spaced lateral projections engaging the disk at the opposite sides, respectively, thereof for preventing movement of the terminal member axially of the disk.
